UNITED STATES PATENT OFFICE

PETER V. GIOË, OF BROOKLYN, NEW YORK

SAFETY ATTACHMENT FOR FLUID BURNERS

Application filed April 21, 1930. Serial No. 446,053.

This invention relates to a safety attachment for fluid burners, and comprehends a re-igniting means which is especially designed for use in connection with the burners of gas cooking stoves and which is adapted to function for the purpose of re-igniting the burners in event the same are extinguished by a draft or as the result of the boiling over of a liquid from a vessel being heated over the burner.

The invention particularly comprehends in connection with valve controlled fluid burners having a burner head formed with a multiplicity of outlets, a safety or re-igniting attachment which includes a conduit, one end thereof constituting an inlet which covers and communicates with at least one of the burner outlets and serves as a means for conducting a portion of the fluid supply to the burner head, from said burner head to a protected outlet end of the conduit to provide a pilot burner independent of the burner head, which pilot burner is disposed in such a position as to be lighted coincident with the lighting of the burner head, and which pilot burner is shielded from drafts or liquids which may operate to extinguish the flame of the burner head proper, whereby said shielded pilot flame will function in the capacity of a means for re-igniting the burner in event of its extinguishment from the above mentioned causes.

The invention as a further object aims to provide a re-igniting device or attachment for fluid burners, especially gas cooking stove burners of the type which are now in general use, which device is so constructed as to lend itself to ready attachment to the burner head or detachment therefrom without necessitating alteration to the burner head or requiring the use of special tools or the services of a skilled mechanic.

Other objects of the invention reside in the comparative simplicity of construction of the device or attachment, the economy with which it may be manufactured and produced and the general efficiency derived therefrom.

With the above recited and other objects in view, reference is had to the following description and accompanying drawing, in

which there is exhibited one example or embodiment of the invention, while the claims define the actual scope of the invention.

In the drawing:

Figure 1 is a plan view of the attachment applied to the conventional form of gas cooking stove burner.

Figure 2 is an enlarged vertical longitudinal sectional view through the device, taken approximately on the line indicated at 2—2 in Figure 1.

Figure 3 is a vertical transverse sectional view taken approximately on the line 3—3 of Figure 2.

Referring to the drawing by characters of reference, A designates a gas burner head of the conventional type which is used on gas cooking stoves and which presents a plurality of radially projecting hollow fingers B, which fingers are formed with burner outlets or apertures C in their upper walls, and which burner head is carried by and communicates with a feed pipe D for admitting the gas or fluid together with air to the burner head A.

The safety attachment or re-igniting device designated generally by the reference character E broadly consists of a conduit or pipe 5, the intake end 6 of which is provided with means which covers and communicates with at least one of the burner outlets and conducts the fluid therefrom to the opposite outlet 7 to provide a pilot flame F at this point which will be lighted coincident with the burner, and which outlet end 7 is formed with means for shielding the pilot light or flame F from drafts or liquids which may tend to extinguish the flame at the other burner outlets.

As illustrated, the means which carries and communicates with the inlet end 6 of the conduit 5 and which covers the burner outlets C is in the nature of a cap or inverted cup shaped element 8 defining a chamber 9 which opens on the under side of the cap 8 to establish communication with one or more of the burner apertures C when the bottom of the cap is disposed in flat contact with the upper surface of one of the fingers B of the burner head.

In order to clamp and retain the cap 8 in

juxtaposition to the burner finger B, the cap is formed as part of a C-clamp 10, the subterposed terminal 11 of which underlies the burner finger and receives therethrough a clamp screw 12 which is adapted to be forcibly advanced against the under side of the burner finger for drawing and impinging the under side of the cap 8 against the upper face of the burner finger.

10 The means at the outlet end 7 of the conduit 5 for shielding the pilot light or flame F consists of a substantially semicircular or concavo-convex hood 13 which is attached or anchored in any suitable manner to the outlet end 7 without obstructing the free exit of the gas or fluid therefrom and which serves to prevent fluids descending from above from affecting the pilot flame F while at the same time shielding said flame F from side or down drafts.

20 As illustrated, the inlet end 6 of the conduit extends through one margin wall of the cap 8 and communicates with the chamber 9. The conduit 5 extends outwardly in a substantially horizontal plane from the cap and is bent upwardly and inwardly at the remaining end which defines the outlet extremity 7.

25 In applying the device or attachment, it is obvious that it is only necessary to associate the cap 8 with any one of the burner fingers B in such a manner that the chamber 9 is in free communication with one or more of the burner apertures or outlet openings C, being sure, of course, that the reversely bent outlet end 7 is directed inwardly towards the center of the burner head A.

30 In use and operation, with the device or attachment applied as illustrated, when the burner is turned on and ignited, the outlet end 7 will be disposed in close enough proximity to the lighted burner to insure the igniting of the pilot flame F coincident with the ignition of the burner. It thus follows that in the event of the burner being extinguished by liquids descending thereon as the result of the boiling over of the same from a vessel being heated over the burner or by down or side drafts, the shielded pilot light or flame F will serve as a means for re-igniting the burner.

35 When the flame is extinguished by liquids descending thereon, the burner head outlets are obstructed temporarily by the liquid and, hence, the full force of the fluid pressure to the burner head will be directed to the pilot burner outlet increasing the pressure at this point and, hence, increasing the length of the pilot flame for more effectually re-igniting the burner head.

40 From the foregoing, it will thus be seen that a safety attachment has been devised, which will effectually act as a means for avoiding the accidental escape of gas or other burner fluids and the possible serious consequences which may result therefrom. While

the invention has been illustrated in its preferred form, it is to be understood that no limitation is intended as to the precise structural details herein disclosed, as it is to be clearly understood that variations and modifications thereof which fall within the scope of the appended claims may be resorted to when found expedient.

70 What is claimed is:

1. A re-igniting device adapted for attachment to a fluid burner head having a plurality of burner apertures comprising an inverted cup shaped element defining a chamber open on the under side and adapted to be secured in contact with the burner head over one of the burner apertures to establish communication between said burner aperture and the chamber, a conduit extending from said member and communicating with said chamber and a shield carried by the opposite outer end of the conduit for protecting the same against extinguishment by drafts or liquid which may descend upon the burner head.

75 2. A re-igniting attachment for fluid burners of the type which are provided with a plurality of burner apertures, said attachment including a conduit, an inverted cup shaped member carried by and communicating with one end of said conduit for engaging over at least one of said burner apertures to receive and convey the fluid to the conduit and means at the opposite end of said conduit for shielding a pilot flame ignited coincident with the lighting of the burner, to protect said pilot flame against extinguishment by drafts or liquids which may descend upon the burner head, whereby said pilot flame serves as a means for re-igniting the burner in event of extinguishment of said burner flame by said causes.

80 3. A re-igniting attachment for a fluid burner of the type which is provided with a plurality of burner apertures, including means communicating with the burner head for receiving a portion of the fluid supplied thereto and for providing a fluid outlet independent of the burner head adapted to be lighted coincident with the lighting of the burner head and protected against extinguishment by drafts or by liquid descending thereon, whereby to serve as a pilot flame for re-igniting the burner flame in event of extinguishment of said burner flame from said causes, said means comprising a cap defining a chamber adapted to be secured in juxtaposition to the burner with the cap chamber in communication with at least one of the burner openings, a conduit extending from the cap and communicating with the cap chamber and a shield carried by the opposite end of the conduit.

85 4. A re-igniting attachment for a fluid burner of the type which is provided with a plurality of burner apertures, including means communicating with the burner head

for receiving a portion of the fluid supplied thereto and for providing a fluid outlet independent of the burner head adapted to be lighted coincident with the lighting of the burner head and protected against extinguishment by drafts or by liquid descending thereon, whereby to serve as a pilot flame for reigniting the burner flame in event of extinguishment of said burner flame from said causes, said means comprising a cap defining a chamber adapted to be secured in juxtaposition to the burner with the cap chamber in communication with at least one of the burner openings, a conduit extending from the cap and communicating with the cap chamber, a shield carried by the opposite end of the conduit and means carried by said cap for removably clamping the same in juxtaposition to the burner.

Signed at Brooklyn in the county of Kings and State of New York this 17 day of April A. D. 1930.
